UNITED STATES PATENT OFFICE.

EDWIN L. KITCHELL, OF NEWARK, NEW JERSEY, ASSIGNOR TO THE CYCLE DANGER SIGNAL COMPANY, OF SAME PLACE.

DESIGN FOR A LAMP.

SPECIFICATION forming part of Design No. 26,509, dated January 12, 1897.

Application filed November 7, 1896. Serial No. 611,412. Term of patent 7 years.

To all whom it may concern:

Be it known that I, EDWIN L. KITCHELL, a citizen of the United States, residing at Newark, county of Essex, and State of New Jersey, have invented a certain new and original Design for Lamps, of which the following is a specification, reference being had to the accompanying drawings, forming part thereof, and in which—

10 Figures 1 and 2 are a front and side view, respectively, of a lamp embodying the features of my novel design; and Fig. 3 is a top view of the same.

The leading features of my design consist 15 in the novel configuration of the lamp-casing, as well as in the ornamentation of the same.

Thus the main body of the lamp consists of a cylindrical portion a , having the curved lower part a' , and an ornamental rim or bead 20 a^2 , said part having the appearance of a bowl, substantially as illustrated. Directly above this bowl-like portion a the upper portion b of the lamp-casing is of an oviform shape, as at b' , while its part is bounded by an ornamental annular bead b^2 , arranged directly 25 above the bead or rim a^2 of the bowl-like part a of the lamp-casing. Said portion b is also provided with ornamental windows or colored-glass jewels e and e' , and is also ornamented 30 with the circular holes b^3 and triangular holes b^4 , as will be clearly evident from an inspection of Figs. 1 and 2. Above the oviform part b' of the portion b is an ornamental hood d , having the upper spherical top d' , provided 35 with ornamental openings d^2 and the out-

wardly-curved surface d^3 . Said surface d^3 is bounded by an annular rim or bead d^4 , and d^5 represents an inwardly-curved convolution which connects the bead d^4 with the oviform portion b' of the lamp-casing. In the convolution d^5 of the hood are ornamental perforations d^6 , as clearly illustrated.

Connected with the upper portion b of the lamp-casing is an angularly-formed bracket c , which when viewed in side elevation forms 45 an inverted $\mathbf{Y}$, the forked ends c' of said $\mathbf{Y}$ being slightly curved, as at c^1 , and circularly formed, as at c^2 .

The particular hood, as well as the bracket herein shown and described, while of my invention are not separately claimed herein, as it will be obvious that the ornamentation of said hood and bracket may be varied without changing the general effect of the lamp, the essential feature of which is the ornamental main body, consisting of the parts a and b , irrespective of any form or configuration of hood or bracket.

Having now described my invention, what I claim is—

The design for the casing of a lamp, substantially as herein shown and described.

In testimony that I claim the invention set forth above I have hereunto set my hand this 2d day of November, 1896.

EDWIN L. KITCHELL.
